CONTROLLING DEVICE FOR DRYING APPARATUS

Filed April 23, 1941

2. Sheets-Sheet 1

Fig. 1. A cross-sectional diagram of a separation unit. A vertical pipe 11 is connected to a horizontal pipe 12. A rectangular frame 10 contains a central circular area. Inside this area, a circular component 36 is surrounded by a ring 39. A horizontal pipe 18 enters from the left, passes through a valve 16, and then splits into two paths: one going up to a valve 20 and another going down to a valve 19. Arrows indicate the flow of material through these valves and into the central circular area. Various numbers (16, 18, 19, 20, 21, 22, 23, 24, 26, 27, 28, 29, 30, 31, 32, 33, 34, 35, 36, 37, 38, 39, 40, 41, 42, 43, 44, 45, 46, 47, 48, 49, 50, 51, 52, 53, 54, 55, 56, 57, 58, 59, 60, 61, 62, 63, 64, 65, 66, 67, 68, 69, 70, 71, 72, 73, 74, 75, 76, 77, 78, 79, 80, 81, 82, 83, 84, 85, 86, 87, 88, 89, 90, 91, 92, 93, 94, 95, 96, 97, 98, 99, 100, 101, 102, 103, 104, 105, 106, 107, 108, 109, 110, 111, 112, 113, 114, 115, 116, 117, 118, 119, 120, 121, 122, 123, 124, 125, 126, 127, 128, 129, 130, 131, 132, 133, 134, 135, 136, 137, 138, 139, 140, 141, 142, 143, 144, 145, 146, 147, 148, 149, 150, 151, 152, 153, 154, 155, 156, 157, 158, 159, 160, 161, 162, 163, 164, 165, 166, 167, 168, 169, 170, 171, 172, 173, 174, 175, 176, 177, 178, 179, 180, 181, 182, 183, 184, 185, 186, 187, 188, 189, 190, 191, 192, 193, 194, 195, 196, 197, 198, 199, 200, 201, 202, 203, 204, 205, 206, 207, 208, 209, 210, 211, 212, 213, 214, 215, 216, 217, 218, 219, 220, 221, 222, 223, 224, 225, 226, 227, 228, 229, 229, 230, 231, 232, 233, 234, 235, 236, 237, 238, 239, 240, 241, 242, 243, 244, 245, 246, 247, 248, 249, 250, 251, 252, 253, 254, 255, 256, 257, 258, 259, 260, 261, 262, 263, 264, 265, 266, 267, 268, 269, 270, 271, 272, 273, 274, 275, 276, 277, 278, 279, 280, 281, 282, 283, 284, 285, 286, 287, 288, 289, 290, 291, 292, 293, 294, 295, 296, 297, 298, 299, 299, 300, 301, 302, 303, 304, 305, 306, 307, 308, 309, 309, 310, 311, 312, 313, 314, 315, 316, 317, 318, 319, 319, 320, 321, 322, 323, 324, 325, 326, 327, 328, 329, 329, 330, 331, 332, 333, 334, 335, 336, 337, 338, 339, 339, 340, 341, 342, 343, 344, 345, 346, 347, 348, 349, 349, 350, 351, 352, 353, 354, 355, 356, 357, 358, 359, 359, 360, 361, 362, 363, 364, 365, 366, 367, 368, 369, 369, 370, 371, 372, 373, 374, 375, 376, 377, 378, 379, 379, 380, 381, 382, 383, 384, 385, 386, 387, 388, 389, 389, 390, 391, 392, 393, 394, 395, 396, 397, 398, 399, 399, 400, 401, 402, 403, 404, 405, 406, 407, 408, 409, 409, 410, 411, 412, 413, 414, 415, 416, 417, 418, 419, 419, 420, 421, 422, 423, 424, 425, 426, 427, 428, 429, 429, 430, 431, 432, 433, 434, 435, 436, 437, 438, 439, 439, 440, 441, 442, 443, 444, 445, 446, 447, 448, 449, 449, 450, 451, 452, 453, 454, 455, 456, 457, 458, 459, 459, 460, 461, 462, 463, 464, 465, 466, 467, 468, 469, 469, 470, 471, 472, 473, 474, 475, 476, 477, 478, 479, 479, 480, 481, 482, 483, 484, 485, 486, 487, 488, 489, 489, 490, 491, 492, 493, 494, 495, 496, 497, 498, 499, 499, 500, 501, 502, 503, 504, 505, 506, 507, 508, 509, 509, 510, 511, 512, 513, 514, 515, 516, 517, 518, 519, 519, 520, 521, 522, 523, 524, 525, 526, 527, 528, 529, 529, 530, 531, 532, 533, 534, 535, 536, 537, 538, 539, 539, 540, 541, 542, 543, 544, 545, 546, 547, 548, 549, 549, 550, 551, 552, 553, 554, 555, 556, 557, 558, 559, 559, 560, 561, 562, 563, 564, 565, 566, 567, 568, 569, 569, 570, 571, 572, 573, 574, 575, 576, 577, 578, 579, 579, 580, 581, 582, 583, 584, 585, 586, 587, 588, 589, 589, 590, 591, 592, 593, 594, 595, 596, 597, 598, 599, 599, 600, 601, 602, 603, 604, 605, 606, 607, 608, 609, 609, 610, 611, 612, 613, 614, 615, 616, 617, 618, 619, 619, 620, 621, 622, 623, 624, 625, 626, 627, 628, 629, 629, 630, 631, 632, 633, 634, 635, 636, 637, 638, 639, 639, 640, 641, 642, 643, 644, 645, 646, 647, 648, 649, 649, 650, 651, 652, 653, 654, 655, 656, 657, 658, 659, 659, 660, 661, 662, 663, 664, 665, 666, 667, 668, 669, 669, 670, 671, 672, 673, 674, 675, 676, 677, 678, 679, 679, 680, 681, 682, 683, 684, 685, 686, 687, 688, 689, 689, 690, 691, 692, 693, 694, 695, 696, 697, 698, 699, 699, 700, 701, 702, 703, 704, 705, 706, 707, 708, 709, 709, 710, 711, 712, 713, 714, 715, 716, 717, 718, 719, 719, 720, 721, 722, 723, 724, 725, 726, 727, 728, 729, 729, 730, 731, 732, 733, 734, 735, 736, 737, 738, 739, 739, 740, 741, 742, 743, 744, 745, 746, 747, 748, 749, 749, 750, 751, 752, 753, 754, 755, 756, 757, 758, 759, 759, 760, 761, 762, 763, 764, 765, 766, 767, 768, 769, 769, 770, 771, 772, 773, 774, 775, 776, 777, 778, 779, 779, 780, 781, 782, 783, 784, 785, 786, 787, 788, 789, 789, 790, 791, 792, 793, 794, 795, 796, 797, 798, 799, 799, 800, 801, 802, 803, 804, 805, 806, 807, 808, 809, 809, 810, 811, 812, 813, 814, 815, 816, 817, 818, 819, 819, 820, 821, 822, 823, 824, 825, 826, 827, 828, 829, 829, 830, 831, 832, 833, 834, 835, 836, 837, 838, 839, 839, 840, 841, 842, 843, 844, 845, 846, 847, 848, 849, 849, 850, 851, 852, 853, 854, 855, 856, 857, 858, 859, 859, 860, 861, 862, 863, 864, 865, 866, 867, 868, 869, 869, 870, 871, 872, 873, 874, 875, 876, 877, 878, 879, 879, 880, 881, 882, 883, 884, 885, 886, 887, 888, 889, 889, 890, 891, 892, 893, 894, 895, 896, 897, 898, 899, 899, 900, 901, 902, 903, 904, 905, 906, 907, 908, 909, 909, 910, 911, 912, 913, 914, 915, 916, 917, 918, 919, 919, 920, 921, 922, 923, 924, 925, 926, 927, 928, 929, 929, 930, 931, 932, 933, 934, 935, 936, 937, 938, 939, 939, 940, 941, 942, 943, 944, 945, 946, 947, 948, 949, 949, 950, 951, 952, 953, 954, 955, 956, 957, 958, 959, 959, 960, 961, 962, 963, 964, 965, 966, 967, 968, 969, 969, 970, 971, 972, 973, 974, 975, 976, 977, 978, 979, 979, 980, 981, 982, 983, 984, 985, 986, 987, 988, 989, 989, 990, 991, 992, 993, 994, 995, 996, 997, 998, 999, 999, 1000, 1001, 1002, 1003, 1004, 1005, 1006, 1007, 1008, 1009, 1009, 1010, 1011, 1012, 1013, 1014, 1015, 1016, 1017, 1018, 1019, 1019, 1020, 1021, 1022, 1023, 1024, 1025, 1026, 1027, 1028, 1029, 1029, 1030, 1031, 1032, 1033, 1034, 1035, 1036, 1037, 1038, 1039, 1039, 1040, 1041, 1042, 1043, 1044, 1045, 1046, 1047, 1048, 1049, 1049, 1050, 1051, 1052, 1053, 1054, 1055, 1056, 1057, 1058, 1059, 1059, 1060, 1061, 1062, 1063, 1064, 1065, 1066, 1067, 1068, 1069, 1069, 1070, 1071, 1072, 1073, 1074, 1075, 1076, 1077, 1078, 1079, 1079, 1080, 1081, 1082, 1083, 1084, 1085, 1086, 1087, 1088, 1089, 1089, 1090, 1091, 1092, 1093, 1094, 1095, 1096, 1097, 1098, 1099, 1099, 1100, 1101, 1102, 1103, 1104, 1105, 1106, 1107, 1108, 1109, 1109, 1110, 1111, 1112, 1113, 1114, 1115, 1116, 1117, 1118, 1119, 1119, 1120, 1121, 1122, 1123, 1124, 1125, 1126, 1127, 1128, 1129, 1129, 1130, 1131, 1132, 1133, 1134, 1135, 1136, 1137, 1138, 1139, 1139, 1140, 1141, 1142, 1143, 1144, 1145, 1146, 1147, 1148, 1149, 1149, 1150, 1151, 1152, 1153, 1154, 1155, 1156, 1157, 1158, 1159, 1159, 1160, 1161, 1162, 1163, 1164, 1165, 1166, 1167, 1168, 1169, 1169, 1170, 1171, 1172, 1173, 1174, 1175, 1176, 1177, 1178, 1179, 1179, 1180, 1181, 1182, 1183, 1184, 1185, 1186, 1187, 1188, 1189, 1189, 1190, 1191, 1192, 1193, 1194, 1195, 1196, 1197, 1198, 1199, 1199, 1200, 1201, 1202, 1203, 1204, 1205, 1206, 1207, 1208, 1209, 1209, 1210, 1211, 1212, 1213, 1214, 1215, 1216, 1217, 1218, 1219, 1219, 1220, 1221, 1222, 1223, 1224, 1225, 1226, 1227, 1228, 1229, 1229, 1230, 1231, 1232, 1233, 1234, 1235, 1236, 1237, 1238, 1239, 1239, 1240, 1241, 1242, 1243, 1244, 1245, 1246, 1247, 1248, 1249, 1249, 1250, 1251, 1252, 1253, 1254, 1255, 1256, 1257, 1258, 1259, 1259, 1260, 1261, 1262, 1263, 1264, 1265, 1266, 1267, 1268, 1269, 1269, 1270, 1271, 1272, 1273, 1274, 1275, 1276, 1277, 1278, 1279, 1279, 1280, 1281, 1282, 1283, 1284, 1285, 1286, 1287, 1288, 1289, 1289, 1290, 1291, 1292, 1293, 1294, 1295, 1296, 1297, 1298, 1299, 1299, 1300, 1301, 1302, 1303, 1304, 1305, 1306, 1307, 1308, 1309, 1309, 1310, 1311, 1312, 1313, 1314, 1315, 1316, 1317, 1318, 1319, 1319, 1320, 1321, 1322, 1323, 1324, 1325, 1326, 1327, 1328, 1329, 1329, 1330, 1331, 1332, 1333, 1334, 1335, 1336, 1337, 1338, 1339, 1339, 1340, 1341, 1342, 1343, 1344, 1345, 1346, 1347, 1348, 1349, 1349, 1350, 1351, 1352, 1353, 1354, 1355, 1356, 1357, 1358, 1359, 1359, 1360, 1361, 1362, 1363, 1364, 1365, 1366, 1367, 1368, 1369, 1369, 1370, 1371, 1372, 1373, 1374, 1375, 1376, 1377, 1378, 1379, 1379, 1380, 1381, 1382, 1383, 1384, 1385, 1386, 1387, 1388, 1389, 1389, 1390, 1391, 1392, 1393, 1394, 1395, 1396, 1397, 1398, 1399, 1399, 1400, 1401, 1402, 1403, 1404, 1405, 1406, 1407, 1408, 1409, 1409, 1410, 1411, 1412, 1413, 1414, 1415, 1416, 1417, 1418, 1419, 1419, 1420, 1421, 1422, 1423, 1424, 1425, 1426, 1427, 1428, 1429, 1429, 1430, 1431, 1432, 1433, 1434, 1435, 1436, 1437, 1438, 1439, 1439, 1440, 1441, 1442, 1443, 1444, 1445, 1446, 1447, 1448, 1449, 1449, 1450, 1451, 1452, 1453, 1454, 1455, 1456, 1457, 1458, 1459, 1459, 1460, 1461, 1462, 1463, 1464, 1465, 1466, 1467, 1468, 1469, 1469, 1470, 1471, 1472, 1473, 1474, 1475, 1476, 1477, 1478, 1479, 1479, 1480, 1481, 1482, 1483, 1484, 1485, 1486, 1487, 1488, 1489, 1489, 1490, 1491, 1492, 1493, 1494, 1495, 1496, 1497, 1498, 1499, 1499, 1500, 1501, 1502, 1503, 1504, 1505, 1506, 1507, 1508, 1509, 1509, 1510, 1511, 1512, 1513, 1514, 1515, 1516, 1517, 1518, 1519, 1519, 1520, 1521, 1522, 1523, 1524, 1525, 1526, 1527, 1528, 1529, 1529, 1530, 1531, 1532, 1533, 1534, 1535, 1536, 1537, 1538, 1539, 1539, 1540, 1541, 1542, 1543, 1544, 1545, 1546, 1547, 1548, 1549, 1549, 1550, 1551, 1552, 1553, 1554, 1555, 1556, 1557, 1558, 1559, 1559, 1560, 1561, 1562, 1563, 1564, 1565, 1566, 1567, 1568, 1569, 1569, 1570, 1571, 1572, 1573, 1574, 1575, 1576, 1577, 1578, 1579, 1579, 1580, 1581, 1582, 1583, 1584, 1585, 1586, 1587, 1588, 1589, 1589, 1590, 1591, 1592, 1593, 1594, 1595, 1596, 1597, 1598, 1599, 1599, 1600, 1601, 1602, 1603, 1604, 1605, 1606, 1607, 1608, 1609, 1609, 1610, 1611, 1612, 1613, 1614, 1615, 1616, 1617, 1618, 1619, 1619, 1620, 1621, 1622, 1623, 1624, 1625, 1626, 1627, 1628, 1629, 1629, 1630, 1631, 1632, 1633, 1634, 1635, 1636, 1637, 1638, 1639, 1639, 1640, 1641, 1642, 1643, 1644, 1645, 1646, 1647, 1648, 1649, 1649, 1650, 1651, 1652, 1653, 1654, 1655, 1656, 1657, 1658, 1659, 1659, 1660, 1661, 1662, 1663, 1664, 1665, 1666, 1667, 1668, 1669, 1669, 1670, 1671, 1672, 1673, 1674, 1675, 1676, 1677, 1678, 1679, 1679, 1680, 1681, 1682, 1683, 1684, 1685, 1686, 1687, 1688, 1689, 1689, 1690, 1691, 1692, 1693, 1694, 1695, 1696, 1697, 1698, 1699, 1699, 1700, 1701, 1702, 1703, 1704, 1705, 1706, 1707, 1708, 1709, 1709, 1710, 1711, 1712, 1713, 1714, 1715, 1716, 1717, 1718, 1719, 1719, 1720, 1721, 1722, 1723, 1724, 1725, 1726, 1727, 1728, 1729, 1729, 1730, 1731, 1732, 1733, 1734, 1735, 1736, 1737, 1738, 1739, 1739, 1740, 1741, 1742, 1743, 1744, 1745, 1746, 1747, 1748, 1749, 1749, 1750, 1751, 1752, 1753, 1754, 1755, 1756, 1757, 1758, 1759, 1759, 1760, 1761, 1762, 1763, 1764, 1765, 1766, 1767, 1768, 1769, 1769, 1770, 1771, 1772, 1773, 1774, 1775, 1776, 1777, 1778, 1779, 1779, 1780, 1781, 1782, 1783, 1784, 1785, 1786, 1787, 1788, 1789, 1789, 1790, 1791, 1792, 1793, 1794, 1795, 1796, 1797, 1798, 1799, 1799, 1800, 1801, 1802, 1803, 1804, 1805, 1806, 1807, 1808, 1809, 1809, 1810, 1811, 1812, 1813, 1814, 1815, 1816, 1817, 1818, 1819, 1819, 1820, 1821, 1822, 1823, 1824, 1825, 1826, 1827, 1828, 1829, 1829, 1830, 1831, 1832, 1833, 1834, 1835, 1836, 1837, 1838, 1839, 1839, 1840, 1841, 1842, 1843, 1844, 1845, 1846, 1847, 1848, 1849, 1849, 1850, 1851, 1852, 1853, 1854, 1855, 1856, 1857, 1858, 1859, 1859, 1860, 1861, 1862, 1863, 1864, 1865, 1866, 1867, 1868, 1869, 1869, 1870, 1871, 1872, 1873, 1874, 1875, 1876, 1877, 1878, 1879, 1879, 1880, 1881, 1882, 1883, 1884, 1885, 1886, 1887, 1888, 1889, 1889, 1890, 1891, 1892, 1893, 1894, 1895, 1896, 1897, 1898, 1899, 1899, 1900, 1901, 1902, 1903, 1904, 1905, 1906, 1907, 1908, 1909, 1909, 1910, 1911, 1912, 1913, 1914, 1915, 1916, 1917, 1918, 1919, 1919, 1920, 1921, 1922, 1923, 1924, 1925, 1926, 1927, 1928, 1929, 1929, 1930, 1931, 1932, 1933, 1934, 1935, 1936, 1937, 1938, 1939, 1939, 1940, 1941, 1942, 1943, 1944, 1945, 1946, 1947, 1948, 1949, 1949, 1950, 1951, 1952, 1953, 1954, 1955, 1956, 1957, 1958, 1959, 1959, 1960, 1961, 1962, 1963, 1964, 1965, 1966, 1967, 1968, 1969, 1969, 1970, 1971, 1972, 1973, 1974, 1975, 1976, 1977, 1978, 1979, 1979, 1980, 1981, 1982, 1983, 1984, 1985, 1986, 1987, 1988, 1989, 1989, 1990, 1991, 1992, 1993, 1994, 1995, 1996, 1997, 1998, 1999, 1999, 2000, 2001, 2002, 2003, 2004, 2005, 2006, 2007, 2008, 2009, 2009, 2010, 2011, 2012, 2013, 2014, 2015, 2016, 2017, 2018, 2019, 2019, 2020, 2021, 2022, 2023, 2024, 2025, 2026, 2027, 2028, 2029, 2029, 2030, 2031, 2032, 2033, 2034, 2035, 2036, 2037, 2038, 2039, 2039, 2040, 2041, 2042, 2043, 2044, 2045, 2046, 2047, 2048, 2049, 2049, 2050, 2051, 2052, 2053, 2054, 2055, 2056, 2057, 2058, 2059, 2059, 2060, 206

CONTROLLING DEVICE FOR DRYING APPARATUS

George G. Crewson, Buffalo, N. Y.

Application April 23, 1941, Serial No. 389,875

3 Claims. (Cl. 34—219)

This invention relates to a controlling device for use in connection with a drying apparatus in which a heated fluid is employed for drying or baking various articles, such as molding cores, breadstuffs, lumber etc. and while the same is hereinafter described in connection with the use of a fluid such as air and gas as the drying medium it is to be understood that the same is equally applicable to apparatus in which a liquid fluid such as fuel oil, is utilized as the drying or heating medium. 10

In many systems of heating, ventilation, drying, baking, etc., a room or compartment is heated by a flow of hot air or gases supplied from an external source such as a furnace or air heater having fluid fuel furnaces, steam coils, electric resistors, etc. Any or all of the following features may be desirable in these systems:

(1) In order to accelerate the heating or drying action, it may be desirable to circulate very considerable volumes of heated air or gas through the drying chamber in order to provide appreciable surface velocities over the material to be dried or heated.

(2) To maintain essentially the same conditions of temperature, humidity, etc., at all points of the drying chamber, hence providing uniformity of heating or drying, it may be desirable to recirculate the heated air or gases in sufficiently large volume that their change of state during one passage through the chamber is small, and the necessary heat increment added to the gases by the heating elements at each cycle in this recirculation.

(3) It may be desirable not only to control the mean temperature, humidity, etc., within the drying chamber, but it may be also desirable to control the maximum temperature, humidity, etc., of the entering gas or air in order that the material in the chamber be not locally subjected to an improper temperature or other condition in an area adjacent to the inlet of the gas or air.

(4) It may be desirable to waste or discard a proportion of the air or gas in circulation at each cycle in order to carry off moisture or other products added to this medium by the action taking place within the drying chamber.

(5) When a portion of the air or gas is thus discarded, it is usually necessary to substitute for it an equivalent makeup volume of air or other gas in order to maintain the required volume in circulation.

Heretofore the flow of the drying medium into and out of the drying and heating chambers, the supply of fresh drying medium to the heating

chamber, and the discharge of spent or waste drying medium to the outer atmosphere was controlled by a plurality of individual valves arranged in passages communicating with respective parts of the drying system which may it difficult to properly adjust the fluid flow to suit the requirements of a particular system or apparatus and to maintain the proper proportion between fluid flow to the several parts in order to secure the most efficient and economical operation of the apparatus.

It is therefore the purpose of this invention to overcome these objections and this is accomplished in accordance with the present invention by employing a single valve or damper controlling device which is located in one place and interconnected with the drying chamber and the heating chamber and also with the fresh air supply and waste or spent air discharge and provided with a unitary valve for adjusting the area of communication between the drying chamber and the heating chamber and the waste discharge, and also between the fresh air supply and the heating chamber, thereby simplifying the controlling apparatus and not only reducing the cost of the same but also rendering the operation of adjusting the apparatus more convenient to meet different working conditions.

In the accompanying drawings:

30. Fig. 1 is a diagrammatic view showing a suitable form of this invention embodied in a drying apparatus in which the heat is derived from an oil or gas burner.

Fig. 2 is a vertical transverse section, on an enlarged scale, taken on line 2—2, Fig. 1 and showing one form of controlling device made in accordance with this invention.

Fig. 3 is a vertical longitudinal section taken on line 3—3, Fig. 2.

Fig. 4 is a vertical longitudinal section, similar to Fig. 3, showing a modified form of the valve and baffle means for controlling the fluid flow relative to the different parts of the apparatus.

45. Fig. 5 is a cross section taken on line 5—5, Fig. 4.

Fig. 6 is a side elevation of the controlling device shown in Figs. 4 and 5.

In the following description similar reference characters indicate like parts in the several figures of the drawings.

Referring to Fig. 1 the numeral 10 represents a drying chamber, oven or kiln in which any desired article may be heat treated, dried or deprived of moisture associated with the articles,

The drying medium such as air or gas at the desired temperature for treating the articles in the drying chamber may be introduced into this chamber by an air delivery pipe, duct or conduit 11 communicating with a fluid inlet 12 on the upper part of the drying chamber and this air together with any gases or vapors which may develop from the action of the air on the articles under treatment may be discharged from this chamber through an outlet pipe, duct or conduit 13 communicating with a fluid outlet 14 on the lower part of the drying chamber.

The numeral 15 represents a furnace or heating chamber in which the gaseous medium such as air taken from the outer atmosphere or elsewhere for treating the articles in the drying chamber and any gases resulting from such treatment are heated. Although any source of heat may be employed as an input of heat in this system a fluid burner 16 of any suitable construction is employed in this instance for burning liquid or gaseous fuel in the heating chamber which burner preferably projects into the lower part of this chamber adjacent to the bottom thereof. The treating fluid such as air or gas or a mixture of the same is introduced by an inlet pipe, duct or conduit 17 which communicates with a treating fluid inlet 18 in the heating chamber adjacent to its bottom and preferably opposite the burner 16.

Propelling means are provided for circulating the air and gases through the heating chamber 15 and the drying chamber 10 which are generally in a closed circulation, which means may be of any suitable construction, but as shown in Fig. 1 comprise a fluid propelling fan or blower having the eye of its casing 19 connected by a pipe or duct 20 with the top of the heating chamber while the outlet of this fan case is connected with the duct 11 leading to the top of the drying chamber 10.

The numeral 21 represents a pipe, duct or conduit through which external or makeup air or other fluid medium is supplied to the apparatus to make up or compensate for any wastage occurring during the drying operation or to supply some special fluid which may be required by the articles under treatment.

The numeral 22 represents a vent stack, duct or conduit through which the waste or spent air or gases are discharged from the apparatus to the outer atmosphere or other place adapted to receive them after treatment of the articles in the drying chamber.

That form of device shown in Figs. 1, 2 and 3 for controlling the interconnection of the various ducts or conduits, establishing communication between the drying and heating chambers, admitting fresh air or fluid, and discharging waste or spent air or fluid in accordance with this invention is constructed as follows:

The numeral 23 represents the cylindrical body of a valve casing which has its opposite ends closed by heads 24, 25. This body is provided in its periphery with a plurality of ports 26, 27, 28, 29 which are arranged in an annular row and in substantially four quarters of this body and which register, respectively, with the drying chamber outlet conduit 13, the inlet conduit 17 of the heating chamber, the fresh air intake or makeup air inlet conduit 21 and the waste or spent air outlet conduit 22 for placing these several conduits in communication with the interior of the valve casing. The circumferential

widths of the ports 26, 27, and 29 are equal but the width of the port 28 in this particular organization of the invention is less than any of the ports 26, 27 and 29 and a neutral or non-effective arc, section or segmental width 30 of the casing body is provided on its cylindrical body between the adjacent sides of the ports 27, 28. The circumferential extent or width of this neutral casing section 30 and that of the port 28 are equal to the circumferential extent of any one of the ports 26, 27 and 29, for a purpose which will be hereinafter explained. The areas of the ports 26, 27 and 29 may be equal or if desired the area of the ports 27 and 26 may be greater than that of port 29.

Within the valve casing is arranged a control valve or damper whereby the flow of fluid through the several ports is controlled and which preferably has the form of a rotatable plate extending diametrically across the casing so as to form two valve wings or members 31, 32 on opposite sides of the axis about which this valve turns. The valve wing 31 is adapted to move into different positions across the port 26 for diverting the fluid escaping from the drying chamber to the heating chamber or to the waste stack or to divide the same between this chamber and the stack, and the valve wing 32 is adapted to move across the port 28 for controlling the intake of fresh air and also adapted to move along the neutral or non-effective area 30 of the valve casing. Turning of the control valve may be accomplished by various means, for example, by an adjusting shaft 33 arranged axially within the body of the casing and extending through bearing openings 34, 35 in the heads thereof and secured to the central part of the plate forming the diverting and intake valve wings 31, 32. Rotation of the valve shaft 33 may be effected either by manually operated means or by automatically operated means which are controlled by a thermostatic mechanism responsive to variation of temperature in the drying chamber or other control station. The means shown in Figs. 1 and 2 are satisfactory for manually adjusting the control valve 31, 32 and holding the same in place after adjustment and as there shown these means comprise an adjusting arm 36 secured to one end of the shaft 33 outside of the valve casing and having a pointer 37 which traverses a scale 38 on the adjacent head of the valve casing, and a thumb screw 39 secured to this arm and passing through a segmental slot in a bracket 40 on the casing and adapted to fasten the valve arm to the bracket after the control valve has been set in the desired position.

Within the valve casing is arranged a stationary baffle 41 which extends radially inward from the body of the valve casing at a point between the ports 28 and 29 to the valve shaft 31 and from one head of the casing to the other so as to cut off direct communication at all times between the fresh air inlet 21 and the waste air outlet 22.

It is to be noted that the size of capacity of the several ports of the casing should be determined by the requirements of a particular installation for treating specific materials inasmuch as an installation may answer the necessary requirements of the capacity if the ports are equal or in any predetermined ratio of areas relative to one another so that a change in the position of the damper or control valve 31, 32 will maintain such predetermined proportion of

port areas regardless of the changed position of this valve or damper.

Assuming that a load of the desired articles has been placed in the drying chamber, that a heater is used in the heating chamber which does not require the addition of any air or other fluid, and that the fan 19 is working, then the operation of the apparatus would be as follows:

Inasmuch as it may be desirable to first bring all of the air in the apparatus up to a predetermined temperature depending upon the character of the articles or materials which are to be dried or treated an initial circulation of the drying fluid is effected through the heating and drying chambers without admitting any fresh air to the apparatus and at this time no air or gases are discharged as wasted from the apparatus. To produce this complete circulation of the treating air and gases in the apparatus the valve 31, 32 is turned into the position within the casing indicated by the dotted lines 311, 321 in Fig. 3, in which this valve extends horizontally from the top of the port 26 to the top of the port 27 and connects the full area of these ports and cuts the same completely from the waste outlet port 29 and the air inlet port 28. In this position of the control valve wings no makeup air is admitted to the apparatus and no waste air or gas is discharged therefrom and the same treating medium is continuously circulated through the apparatus by the fan 19.

If the means for heating the air are of a character which require the addition of air, such as the oil or gas burner 16 shown in Fig. 1 to which air must be supplied to support combustion then the control valve is turned in the casing so that its wings 31, 32 initially occupy the position indicated by the dotted lines 312 and 322 in Fig. 3, and extend from the bottom of the port 28 to a point below the top of the port 26 a distance equal to the width of the dwell, neutral or ineffective area 30 of the valve casing. When the control valve is thus placed the entrance of fresh external air to the apparatus is still completely cut off and only a small part of the gaseous fluid is permitted to escape as waste from the drying chamber through the outlet conduit 13, port 26, valve casing 23, port 29 and waste conduit 22 to the outer atmosphere while the remaining greater part of the gaseous medium is conducted through the lower part of the port 26, valve casing 23, port 27 and conduit 17 to the heating chamber whereby the retained gaseous medium is heated and again delivered by the fan to the drying chamber for recirculation through the apparatus until the desired temperature has been attained in the drying chamber.

The extent of the non-effective movement of the intake wing 32 of the valve from its lowermost position shown at 321 to the position 322 at the bottom of the port 28 is usually calculated to compensate for the amount of air which is supplied to the fluid burner for combustion purposes so that the volume of fluid in circulation will always remain constant and only such an amount of the treating fluid will be permitted to escape through the waste conduit 22 as can pass through that part of the port 26 between its top and the diverting wing 31 while the latter is in the position indicated by dotted lines 312 in Fig. 3, whereby the addition of air to the fluid burner is balanced by the discharge of waste gas through the stack 22 and the volume of gaseous medium in circulation remains the same.

In case the articles under treatment are of such character that it is necessary to continuously discharge or waste some of the gaseous medium in excess of that equivalent to the products of combustion due to the same becoming laden with moisture from the articles, or for other reasons, the volume of gaseous medium in circulation is maintained constant by admitting an amount of external makeup air to the apparatus equal in amount to that which is wasted or discharged from the apparatus. This is accomplished by turning the controlling valve so that the front or intake wing 32 is raised above the bottom of the fresh air inlet port 28, as indicated by full lines in Fig. 3, and thus open this port to some extent and the rear or diverting wing 31 is lowered a greater extent from the top of the port 28, as shown by full lines in the same figure, thereby permitting more of the gaseous medium to be discharged from the outlet conduit 13 of the drying chamber to the waste conduit 22 and to the outer atmosphere and less to pass on to the heating chamber 15 for reheat-
10 ing the retained gaseous medium and returning the same to the drying chamber. The extent
15 which the intake valve wing 32 opens the make-
up or fresh air port 28 and the extent which the
diverting valve wing 31 divides and distributes
20 the stream of gaseous medium issuing from dry-
ing chamber 10 between the heating chamber
25 and waste outlet is governed by the requirements
of the articles in the drying chamber. Regard-
less however of the position of the controlling
valve wings a constant proportion is maintained
30 between the incoming makeup air together with
the fluid added thereto by the gases from the
heating burner as compared with the volume of
35 fluid discharged from the drying chamber and
delivered partly to the heating chamber and
partly to the waste outlet, so that the volume
40 of fluid in circulation is always the same, not-
withstanding that the amount of fresh air ad-
mitted and the amount of spent air and gas dis-
charged may be varied to suit the requirements
45 of the particular articles which are being treated.

A position of the control valve similar to the position 31, 32 shown in Fig. 3 may be desirable when it is necessary to admit fresh air for the purpose of maintaining an oxidizing atmosphere
50 in the oven or drying chamber when the necessity for the admission of such air also requires proportionate wastage to the outlet 22 leading to the stack.

For the purpose of operating the apparatus
55 without recirculating any of the gaseous medium after the same has been used once in the treatment of the articles in the drying chamber the controlling valve is adjusted so that its front wing 32 is in line with the top of the intake or
60 fresh air port 28, as indicated by dotted lines
323, in Fig. 3, thereby opening this port to the fullest extent, and the rear or diverting wing 31
65 of this valve is in line with the bottom of the port 26, as shown by dotted lines 313 in this figure, whereby the outlet of the drying chamber is completely cut off from direct communication with the heating chamber and all of the gaseous medium escaping from drying chamber is dis-
70 charged into the waste conduit 22, while the intake port 28 is opened to its fullest extent and the maximum amount of fresh air is permitted to enter the heating chamber.

It will therefore be apparent that when the control valve is in the position 313, 323 just de-
75 scribed that no recirculation of the fresh air

entering the port 28 or products of combustion from the burner occurs from the port 26 to the port 27 and that complete wastage of the treating medium is effected through the port 29 after the same has once operated on the articles under treatment in the oven 10.

It may be desirable to hold the temperature in the oven for a time after the maximum desired temperature has been reached in order to complete a desired reaction therein. For this purpose the burner is shut off either manually or by thermostatically controlled means and turned on again periodically, as required to maintain the desired temperature in the oven. But when the burner is turned off and no products of combustion are added to the circulation then no wastage should occur to the stack. Under these circumstances the damper or control valve should occupy the position shown at 311, 321 in Fig. 3. A similar position of the control valve would be required when the burner or heater is turned off for the purpose of permitting the oven to cool slowly and to induce advantageous uniformity of the cooling effect.

Instead of making the wings 31, 32 of the controlling valve integral, as shown in Fig. 3, so that they are non-adjustable relative to each other and also employing a baffle which always occupies a fixed position, as shown at 41 in the same figure, these valve wings, as shown at 310 and 320 in Fig. 4, may be made adjustable relative to each other in a direction circumferentially of the cylindrical body 23 of the valve casing. As there shown the fluid intake valve wing 320 is separate from the fluid diverting valve wing 310 and adapted to sweep with its outer edge relative to the fluid intake port 28 so as to occupy either a wholly closed position, as indicated by full lines in Fig. 4, or a wholly open position, as indicated by dotted lines 325 in this figure, or a partly open position as indicated by dotted lines 326 in this figure. At its inner edge the fluid intake valve wing 320 is connected with an adjusting shaft 42 which is arranged axially in the valve casing and provided at one of its ends externally of the casing with an adjusting arm 43, whereby the valve wing 320 may be moved into the desired position relative to the fluid intake port 28. The fluid diverting valve wing 310 is adapted to sweep with its outer edge relative to the outlet port 26 of the drying chamber into a position in which the outlet of the latter is either wholly cut off from the waste discharge conduit 22, as shown by full lines in Fig. 4, to effect complete circulation of the treating fluid through the drying chamber or the outlet of the drying chamber may be wholly cut off from the heating chamber, as shown by dotted lines 315 in this figure for causing the treating fluid to pass only once through the drying chamber, or this diverting valve may be placed in an intermediate position, as indicated by dotted lines 316 in this figure for causing the fluid escaping from the outlet of the drying chamber to be delivered partly to the waste conduit 22 and partly to the heating chamber inlet 17. At its inner edge the diverting valve wing 310 is connected with a tubular or quill shaped shaft 44 arranged around the shaft 42 and journaled at its opposite ends in the heads of the body of the valve casing, as shown in Fig. 5. At one of its ends the tubular shaft 44 is provided with an adjusting arm 45 which is arranged on the exterior of the valve casing and whereby the posi-

tion of the diverting valve wing 310 may be adjusted relative to the port 26. The positions of the intake valve wing and the diverting valve wing relative to their respective ports may be determined by means of pointers 46, 47 arranged on the valve arms 43, 45, respectively, and traversing segmental scales 48, 49 arranged, respectively, on the arm 45 and on the casing and after these valve wings have been located as desired the same may be held in place by a clamping screw 50 passing through an opening in the arm 43, a segmental slot in the arm 45 and a segmental slot in a bracket 51 on the valve casing. The arms 43 and 45 are arranged, respectively, on the outer and inner sides of the bracket 51, as shown in Fig. 5 whereby upon tightening the screw 50 the valve wings 310, 320 will be secured in their adjusted positions.

In the construction shown in Fig. 4, the casing 20 is provided with a neutral area 301 across which the intake wing 320 can move idly from the position shown by dotted lines 327 in Fig. 4 to the position shown by full lines in the same figure and thereby permit of an idle motion of this wing 25 without opening the intake 21 during the initial part of the movement of the diverting wing 310 for connecting the drying chamber outlet 13 with the waste vent 22 in a manner resembling that described with reference to Fig. 3.

30 The baffle 411 in the construction shown in Fig. 4 is movable circumferentially within the valve casing about the axis thereof and is connected at its inner edge with the tubular shaft or quill 44 so as to move in unison with the diverting valve wing 310 of which it virtually forms an integral part. At its outer edge the movable baffle 411 sweeps idly along a blank area or space 52 on the valve casing between the fluid intake port 28 and the waste fluid port 29, it being immaterial as to what particular part of this blank area is engaged by the baffle 411 inasmuch as the same always operates as a partition or wall which prevents direct communication between the intake port 28 and the waste port 29. This idle movement of the baffle 411 extends from the position shown by full lines in Fig. 4 to the position indicated by dotted lines 412 in the same figure and corresponds to the extent which the diverting valve wing 310 moves from the position in which the latter cuts off the drying chamber completely from the vent stack 22, as shown by full lines in Fig. 4, to the position in which the diverting valve wing 311 completely cuts off the drying chamber from the heating chamber, as shown by dotted lines 315 in Fig. 4.

In the construction shown in Fig. 3 the valves 31 and 32 move in unison so that upon turning the shaft 33 both of these valves are turned at the same time.

60 In the construction shown in Fig. 4 the valves 310 and 320 are adjusted independently of one another within the limits of the slot in the arm 45 but these valves are held in place after adjustment by a single clamping device 50.

65 It will be noted that in this invention it is possible to effect complete recirculation of the treating fluid through the apparatus, also to cause the treating fluid to operate but once during each cycle on the articles in the treating chamber and also to maintain a predetermined proportion between that part of the flow of treating fluid which is recirculated and that part which is wasted so that the combined ducts or conduits which carry the treating fluid are al-

ways of equal area and therefore do not restrict or throttle the flow of treating fluid when varying the proportions between the makeup air coming in through the fluid intake and the waste fluid discharged through the vent stack. The foregoing results are obtained by adjusting only one controlling unit inasmuch as the pair of valve wings 31, 32 move in unison and permit of recirculation or non-recirculation of the treating fluid to be effected at any point between zero and full flow capacity, and compensation for the desired wastage is automatically effected by the simultaneous admission of a corresponding amount of makeup air or fluid.

This is particularly advantageous in certain installations or applications, such as baking cores in the ovens of foundries, in which the heat is supplied by means of combustion in a furnace, the combustion products of which become a part of the circulation gases. These products of combustion therefore add to the volume of treating medium and must be continuously discharged from the system. In such cases it is necessary that some opening or communication between the port 26 and the port 29 should occur before there is any opening of the port 28. Further, in some drying operations, such as drying foundry cores, the presence of excess oxygen in the combustion or recirculation gases, is of importance for the purpose of oxidizing the binders used in the cores. Also, with an oven under thermostatic control, wherein after reaching or approaching the desired temperature, the combustion may be intermittent, and when it is desired to maintain the oven temperature most economically, there should be neither wastage of circulating gases nor cold air admitted during the periods when the thermostatic control interrupts further combustion in the furnace.

The construction of the proportioning flow damper or controlling valve mechanism shown in Figs. 2 and 3 is well suited for use in connection with such an oven for drying foundry cores. It is to be noted that in the organization disclosed in Fig. 3 the initial part of the movement of the wing 32 from the position 321 to the position 322 no opening of the intake 28 occurs but the valve wing 31, due to its moving to the position indicated at 312, opens the port 28 partly and permits some wastage of gaseous medium to the vent port 29 before any makeup air enters the system through the intake port 28. The position of the valve wings, as shown by full lines 312, 322 in Fig. 3 therefore establishes just enough communication between the drying chamber outlet port 26 and the waste port 29 to allow escape of gases corresponding to the amount added to the stream of treating fluid by the fuel burner in the heating chamber or furnace, hence no makeup air is required. If further wastage is required then the valve wing 31 is moved to the position shown by full lines in Fig. 3 and thus increase the area of communication between the drying chamber outlet and the waste or vent while at the same time the area of communication between this outlet and the heating chamber is reduced and sufficient makeup air is added by moving the intake wing to the full line position 32 in Fig. 3 in order to compensate for this increased wastage.

As an example of the application of this device, the baking of sand cores as used in foundry practice may be considered.

These cores are frequently made of sand

bonded together with an oil binder. The sand may, and usually will, contain appreciable moisture as well as the binder. The purpose of the baking is to first drive off the moisture and more volatile components in the binders, and, second, to sufficiently oxidize the binder so that the sand particles are well cemented together.

It is important that the core be not subjected to too high a temperature or at high temperatures for too long a period, as in such case the binder is carbonized and loses its cementing properties. Both the speed of drying and the speed of oxidation are increased with velocity of circulation within the oven.

15 To prevent localized oven heating and non-uniform baking throughout the entire oven, the combustion gases furnishing the heat, must be tempered to a safe entering temperature, either by recirculation, or by admission of excess air.

20 During the initial drying operation, much heat is required but no excess of oxygen. Thus position 312, 322 of valve or damper, as shown in Fig. 3, would be proper, this providing for maximum recirculation without admission of excess air, yet permitting a stack wastage equal to the products of combustion added in the furnace or heating chamber.

When all the moisture has been driven off the cores, the temperature which has previously been held down by the heat required for evaporation, rises, and the oxidation period occurs. Then a valve position similar to that indicated at 31, 32 in Fig. 3 would be proper. When maximum temperature is reached, the thermostatic control, if one is employed, would automatically stop combustion in the furnace. Thus, since no combustion gases are being added, and it being desirable to just maintain temperature, there should be neither wastage to the stack nor admission of air so that position indicated at 311, 321 in Fig. 3 would immediately become desirable.

In practice, a position approximating 31, 32 can generally be determined by experience as to which is most beneficial, and a setting made accordingly. Automatic control means can then change the dampers to positions 311—321, 312—322 and 313—323 for the several periods, thus eliminating the uncertainty of manual operation.

50 While this device is primarily designed for gas flows in drying and baking work, the same principle is applicable to fluid flows, either liquid or gaseous, and for any operation in which a continuous circulation of a fluid must be supplemented by discharge of a part of the same and an equivalent makeup supplied from another source.

For convenience in described this invention it is to be understood that the term "air" as occasionally used herein is intended to include any form of gaseous fluid as air, gas or similar medium.

Although the apparatus herein shown and described, sets forth mainly one in which the controlling valve means are adjusted manually it is to be understood that these valve means may be adjusted automatically by a thermostatic shifting mechanism which is responsive to changes in temperature in the drying chamber or other place of which the temperature governs the operation of a system in which this invention forms a part.

I claim as my invention:

1. A controlling device for drying apparatus comprising a casing having a cylindrical wall

provided with a fresh air inlet, an outlet to a heating chamber, an inlet from a drying chamber and a spent air outlet arranged in a circumferential row in the order named, said fresh air inlet and the inlet from the drying chamber being of different widths circumferentially, and said fresh air inlet being spaced circumferentially by a dwell area from the outlet to the heating chamber which equals the difference in widths between said fresh air inlet and the inlet from the drying chamber, a rotary valve pivoted centrally in said casing to turn about the axis thereof and having a part on one side of its axis movable across said fresh air inlet and dwell area and a part on the opposite side of its axis movable across said inlet from the drying chamber, and a baffle extending from said wall between the fresh air inlet and spent air outlet to the axis of said valve.

2. A controlling device for drying apparatus comprising a casing having a cylindrical wall provided with a fresh air inlet, an outlet to a heating chamber, an inlet from a drying chamber and a spent air outlet arranged in a circumferential row in the order named, said fresh air inlet and the inlet from the drying chamber being of different widths circumferentially, and said fresh air inlet being spaced circumferentially by a dwell area from the outlet to the heating chamber which equals the difference in widths between said fresh air inlet and the inlet from the drying chamber, a rotary valve pivoted centrally in said casing to turn about the axis thereof and having a part on one side of its axis movable across said fresh air inlet and dwell area and a part on the opposite side of its axis movable across said inlet from the drying chamber.

- 5 drying chamber, a baffle extending from said wall between the fresh air inlet and spent air outlet to the axis of said valve, and means for adjusting said baffle circumferentially between said fresh air inlet and said spent air outlet.
- 10 3. A controlling device for drying apparatus comprising a casing having a cylindrical wall provided with a fresh air inlet, an outlet to a heating chamber, an inlet from a drying chamber and a spent air outlet arranged in a circumferential row in the order named, said fresh air inlet 15 and the inlet from the drying chamber being of different widths circumferentially, and said fresh air inlet being spaced circumferentially by a dwell area from the outlet to the heating chamber which equals the difference in widths between said fresh air inlet and the inlet from the drying chamber, a rotary valve pivoted centrally in said casing to turn about the axis thereof 20 and having a part on one side of its axis movable across said fresh air inlet and dwell area and a part on the opposite side of its axis movable across said inlet from the drying chamber, a baffle extending from said wall between the 25 fresh air inlet and spent air outlet to the axis of said valve, and means for adjusting said baffle circumferentially between said fresh air inlet and said spent air outlet including concentric members carrying said valve and baffle, respectively, adjusting arms arranged externally 30 of the casing and connected respectively with said members, a segment which is mounted on said casing and relative to which said arms are moved, and means for securing said arms in position relative to different parts of said segment.

GEORGE G. CREWSON.
